[57] CLAIM

The ornamental design for a screwdriver handle, as shown and described.

DESCRIPTION

FIG. 1 is a side elevational view of one side of the screwdriver handle constituting our new design;
FIG. 2 is a front elevational view thereof;
FIG. 3 is a rear elevational view thereof;
FIG. 4 is a top plan view thereof;
FIG. 5 is a bottom plan view thereof; and,
FIG. 6 is a side elevational view of the other side thereof. The broken line portions of the drawing are for illustrative purposes only and form no part of the claimed design.
